[57] **CLAIM**

The ornamental design for an adaptor for inner bearing ring bore, as shown and described.

DESCRIPTION

FIG. 1 is an isometric view of the front, top and right side of an adaptor for inner bearing ring bore showing my design; FIG. 2 is a front view with the rear view being identical in appearance;

FIG. 3 is an enlarged, fragmented front detailed view of my adaptor for inner bearing ring bore;

FIG. 4 is a top view with the bottom view and adjacent views being identical in appearance; and,

FIG. 5 is an enlarged, fragmented sectional view of my adaptor for inner bearing ring bore as indicated by line 5—5 of FIG. 2.

The view of FIGS. 3 and 5 are shown fragmented and enlarged for clarity of illustration.
